UNITED STATES PATENT OFFICE

2,577,583

TIME SWITCH ATTACHMENT FOR ALARM CLOCKS

Glenn J. Hines, Minneapolis, Minn.

Application July 7, 1947, Serial No. 759,445

1 Claim. (Cl. 200—35)

1

My invention relates to improvements in time switches and, more particularly, to a time switch attachment for an ordinary alarm clock.

The principal object of this invention is to provide a compact and highly efficient time switch that is applicable to an ordinary alarm clock, as a self-contained unit, to be actuated by the alarm wind key of the clock for turning "on" or "off," at a predetermined time, a radio, an incandescent lamp, an electric appliance, an electric machine and the like.

A further object of this invention is to provide a highly efficient time switch that can be manually set to be operated by the alarm wind key of an alarm clock, that turns either clockwise or counter-clockwise while the alarm is sounding.

A still further object of this invention is to provide a novel time switch that automatically stops the turning of the alarm wind key, during the sounding of the alarm, as soon as the time switch has been actuated by the turning of said wind key.

Another object of this invention is to provide novel means for attaching a time switch unit to an ordinary alarm clock, to be actuated by the alarm wind key thereof, by the use of a screw or other part of the alarm clock.

Other objects of the invention will be apparent from the following description, reference being had to the drawings.

To the above end, generally stated, the invention consists of the novel devices and combination of devices hereinafter described and defined in the claim.

In the accompanying drawings, which illustrate one embodiment of the invention, like characters indicate like parts throughout the several views.

Referring to the drawings:

Fig. 1 is a rear elevational view of an alarm clock to which the improved time switch is attached;

Fig. 2 is an elevational view, on an enlarged scale, of the time switch with the back section of its case removed to expose the parts of the time switch within the case, the wiring being shown in diagram;

Fig. 3 is a rear end elevation of the time switch attachment, some parts being broken away and sectioned and also showing in rear elevation a fragment of the alarm clock;

Fig. 4 is a rear elevational view of the time switch attachment with parts of the alarm clock sectioned on the line 4—4 of Fig. 3;

Figs. 5, 6 and 7 are fragmentary detail views

2

principally in section taken on the lines 5—5, 6—6 and 7—7 of Fig. 2, respectively; and

Fig. 8 is a wiring diagram.

For the purpose of showing the invention in working position, there is shown in the drawings an ordinary alarm clock indicated, as an entirety, by the numeral 9, with the exception of its alarm wind key 10, and the retaining screw 11 for the back member of the clock. In the 10 wiring diagram, the time switch attachment is shown for turning "off" an incandescent lamp 12, see Fig. 8.

Referring now in detail to the improved time switch attachment for the alarm clock 9, the 15 numeral 13 indicates a rectangular case of suitable insulating material. This case 13 includes a front section 14 and a rear section 15 detachably connected by a nut-equipped bolt 16.

The case 13 is detachably secured to the back member of the clock 9 by a relatively long arm 17 having a semi-circular T-head 18 provided with a semi-circular slot 19 that is concentric with the perimeter of said head. In the arm 17 is a longitudinal slot 20 and in the back of the 25 case section 15 is a plurality of screw-threaded holes 21 that are equally spaced apart transversely of the case 13.

The T-head 18 is adjustably and detachably pivoted to the case section 15 by a screw 22 that 30 extends through a hole in said head, at the axis thereof, and secured in one of the screw-threaded holes 21. This T-head 18 is releasably held against pivotal movement on the screw 22 by a second screw 23 that extends through the slot 20, is secured in one of the screw-threaded holes 35 21 and frictionally clamps the T-head 18 onto the case section 15. The arm 17 is adjustably and rigidly clamped onto the back member of the clock 9 by the screw 11 that extends through the slot 20 in said arm. The purpose of adjustably attaching the arm 17 to the case 13 is to adapt said arm for attachment to an alarm clock by one of the screws or other member in the back thereof.

45 The invention includes an automatic time switch A and a manually operated secondary switch B. The time switch A includes a conductor plate 24 within the case 13 and secured to the case section 14 thereof. This conductor 50 plate 24 is provided with a terminal screw 25 and a contact 26 provided with a terminal screw 27. On the case section 14 is a contact 28 that overlies the conductor plate 24 and provided with a terminal nut-equipped bolt 29. For contact with either one of the contacts 26—28 is a

movable contact arm 30 pivoted at 31 to the conductor plate 24.

The movable contact arm 30 is operated from the alarm wind key 10 by the following connections, to wit: an insulating shaft 32 having on its inner end a hub 33 provided with a transverse slot 34 into which the alarm wind key 10 loosely extends. Said hub 33 and slot 34 afford a clutch member. On the outer end of the shaft 32 is a knob 35 by which said shaft may be 10 manually turned to cock the alarm wind key 10. The shaft 32 is further provided with a radial arm 36 connected to the contact arm 30 by a coiled spring 37 held under tension and completes the operating connections from the shaft 32 to 15 the contact arm 30.

The shaft 32 extends transversely of the case 13 and its front end portion extends through a hole 38 in the case section 14 and said section affords a bearing therefor. Formed in the shaft 32 is an annular groove 39 into which the case section 14 extends and holds said shaft against endwise movement relative to the case 13. The hub 33 extends through a hole 40 in the case section 15 and said section affords a bearing 25 for the hub 33.

On the case section 14 is a pair of circumferentially spaced stop pins 41 and 42 between which the arm 36 projects. These stop pins 41 and 42 limit the swinging movement of the arm 36 and hence the turning of the shaft 32 by the turning of the alarm wind key 10 during the sounding of the alarm.

As shown in the drawings, the alarm wind key 10 is in cocked position, the arm 36 is in engagement with the stop pin 41 and the contact arm 30 is engaging the contact 26. To cock the alarm wind key 10, the shaft 32 is manually turned clockwise by the knob 35. The time switch A, as shown in Fig. 8, is closed and the lamp 12 is lit.

When the time has arrived for the sounding of the alarm and the turning "off" of the lamp 12, the alarm wind key 10 is turned by the block mechanism and in turn turns the shaft 32 which moves the arm 36 toward the stop pin 42. As the arm 36 moves toward the stop pin 42, it swings the spring 37 past dead center. The tensioned spring 37, having been moved past dead center, draws the contact arm 30 out of engagement with the contact 26 and swings the same into engagement with the contact 28 which opens the time switch A. The stopping of the arm 36 by its engagement with the pin 42 also automatically stops the alarm being sounded.

The manually operated secondary switch B includes fixed contacts 43 and 44 in an insulating housing 45 on the case section 14. These contacts 43 and 44 have terminal screws 46 and 47, respectively. A conductor arm 48 in the housing 45 is pivoted to the case section 14 by a nut-equipped bolt 49 for engagement with either one of the contacts 43 or 44. As shown, the contact arm 48 is in engagement with the fixed contact 43. The alarm wind key 10 turns counter-clockwise when moving from a cocked position. For an alarm wind key that turns clockwise from a cocked position, the contact arm 48 will be moved into engagement with the fixed contact 44. On the outer end of the contact arm 48 is an insulating hand-piece 50.

Within the case 13 is a pair of spring contacts 51 and 52 secured to said case and having terminal screws 53 and 54, respectively. A lamp cord 55 has wires 56 and 57 to which, at one of their ends, a conventional plug 58 is attached in the customary manner. This plug 58 may be connected to any suitable outlet leading from a source of electrical energy, not shown. The wires 56 and 57, at their other ends, are attached, the former to the terminal screw 49 and the latter to the terminal screw 54.

A wire 59 connects the terminals 25 and 53, a wire 60 connects the terminals 29 and 41, and a wire 61 connects the terminals 27 and 46. A lamp cord 62 connects the lamp 12 to the time switch. The wires 63 and 64 of the lamp cord 62 are attached at one of their ends to a coupling plug 65 electrically connected to the spring contacts 51 and 52.

Obviously, in place of the lamp 12, a radio, an electric appliance, or an electric machine having in its electric circuit a plug similar to the plug 65 may be connected to the time switch to be turned "on" or "off" thereby at a predetermined time.

From the above description, it is evident that the time switch attachment may be very quickly and easily applied to an ordinary alarm clock simply by removing one of the retaining screws 23 for the back member thereof, loosening the screw 23, in inserting the removed retaining screw through the slot 28 and replacing the same to frictionally clamp the arm 17 onto the back member of the clock and finally in tightening the screw 23 to frictionally clamp the T-head 18 onto the case 13 to prevent pivotal movement of said head on the screw 22. In applying the time switch attachment to a clock movement of the case 13 toward the clock, the alarm wind key 10 will be inserted into the slot 35 and thus couple the shaft 32 to the alarm wind key.

It will be understood that the invention described is capable of various modifications within the scope of the invention herein disclosed and claimed.

What I claim is:

A time-controlled electric switch in the form of a self-contained unit including a case having means for operating the wind member of an alarm clock, an arm having on one end a head pivoted to the case, said head having a slot on the arc of a circle having its center at the axis of the pivot for the head, and a set screw extending through said slot and having threaded engagement with the case for locking the head against pivotal movement, said arm having a longitudinal slot for a screw holding the back member of the alarm clock in place to attach the case to the alarm clock.
